(57) **CLAIM**

We claim the ornamental design for a food pan, as shown and described.

DESCRIPTION

FIG. 1 is a top perspective view of one example embodiment of a food pan;

FIG. 2 is a top plan view thereof;

FIG. 3 is a front elevational view thereof;

FIG. 4 is a right end elevation view thereof;

FIG. 5 is a rear elevational view thereof;

FIG. 6 is a bottom plan view thereof;

FIG. 7 is a sectional view thereof taken along line 7-7 of FIG. 2; and,

FIG. 8 is a left end elevational view thereof.

The ornamental design which is claimed is shown in solid lines in the drawings. The portions in broken lines are shown broken away to indicate no particular height is claimed beyond what is shown in solid lines.
